(57) **CLAIM**

The ornamental design for a beverage tap handle with mount for identification tags, as shown and described.

DESCRIPTION

FIG. 1 is a perspective view of a first embodiment of a beverage tap handle with mount for identification tags showing my new design;

FIG. 2 is a front view thereof; the rear view being a mirror image thereof;

FIG. 3 is a right side view thereof; the left side view being a mirror image thereof;

FIG. 4 is a top plan view thereof;

FIG. 5 is a bottom view thereof;

FIG. 6 is a perspective view of a second embodiment of a beverage tap handle with mount for identification tags;

FIG. 7 is a front view thereof; the rear view being a mirror image thereof;

FIG. 8 is a right side view thereof;

FIG. 9 is a left side view thereof;

FIG. 10 is a top plan view thereof;

FIG. 11 is a bottom view thereof;

FIG. 12 is a perspective view of a third embodiment of a beverage tap handle with mount for identification tags;

FIG. 13 is a front view thereof; the rear view being a mirror image thereof; ps FIG. 14 is a right side view thereof;

FIG. 15 is a left side view thereof;

FIG. 16 is a top plan view thereof; and,

FIG. 17 is a bottom view thereof.

The broken line showing in the figure drawings are included for the purpose of illustration and form no part of the claimed design.

1 Claim, 9 Drawing Sheets
